POWER GENERATING UNIT AND IGNITING
MEANS THEREFOR

Roscoe A. Coffman, Hollywood, Calif.

Application April 23, 1936, Serial No. 76,059
In Germany February 8, 1935

21 Claims. (Cl. 102—12)

This invention relates to pressure creating units and method of applying the same. A device of this general character is illustrated in my U. S. Patent No. 2,005,913, issued June 25, 1935, upon an application filed May 11, 1931, and also in my pending application, Serial No. 581,032, filed December 14, 1931, where there is disclosed a cartridge for generating pressure to be utilized in an expansion motor for internal combustion engine starters. While the cartridge of the present invention is of utility in the same relation, I wish to make it clear at the outset that it is by no means limited to that particular field, but that it has a wide range of applicability, and that it is intended to be used in any relation where a self-contained pressure generating unit may be employed to advantage. Therefore, merely as a means of bringing out certain characteristics of the device, I have illustrated in the accompanying drawings a part of the system disclosed in my patent aforesaid, but it is to be understood that this is not to be construed as limiting with respect to the uses to which the invention may be put, nor necessarily as a part of the invention.

The major object of this invention is to provide a small portable unit assembly, capable of generating within a closed system, a sufficient volume of gases, and superheating the same to a maximum of expansion to pressures sufficiently low to be accurately controlled, but great enough to, within a limited space, develop a preponderance of horse power sufficiently great to perform a given amount of useful work when used in connection with a device adapted to receive the same.

Another object of the invention is to provide in such unit assembly a fuel capable of generating gases and superheating same at a predetermined rate sufficiently rapid to perform the determined work operation, yet sufficiently slow to avoid injurious shock to the device or mechanisms to which the resulting power is transmitted.

A further object of the invention is to provide a fuel sufficiently slow burning as to be capable when ignited, of propelling a major portion of the fuel contained in the unit to a point remote from the initial point of the ignition and there burned to maintain the necessary pressure.

Another object is to provide in such unit a non-detonating igniting means producing a flame of sufficient duration and heat to insure the ignition and combustion of the fuel within said unit,

Another object resides in the construction of the unit whereby provision is made so that after ignition of the igniting means the pressure developed by the combustion of the fuels, regardless of the amount of pressure required for operation, will not extinguish the flame, due to the fact that nitroglycerine (easily ignitable and hard to extinguish) fuels have been ignited and therefore the pressure will not snuff out the flames of the slow-burning (nitro-cellulose) fuel. This is accomplished by the proper blending of fuels, such as nitroglycerine bearing fuels in the various percentages with nitro-cellulose or other non-nitro-glycerine bearing fuels as fully set forth herein.

A still further object of the invention resides in the construction of the unit charge whereby provision is made for igniting the fuel at or near the forward end of said unit and thus permitting the fuel within the shell or cartridge to be withdrawn therefrom in a comparatively steady stream into the system as the burning of the fuel progresses. This is accomplished in part by the provision of an igniting tube extending through the fuel for creating a train of fire through the unit, and is particularly useful in the longer types of these power generating units.

A further object of the invention is to provide a power generating unit of the character disclosed wherein a hot flash match is used, and where an igniting tube is associated therewith extending from said match through the fuel charge within the unit and in a direction longitudinally of the unit, said tube not only serving to ignite the fuel throughout its length, but also acting as a conveying means, through the body of fuel, for the flame from the hot flash match, and for the purposes intended.

Another object of the invention resides in the construction of such a power generating unit wherein provision is made for conveying a continuous hot flash flame from the primary igniting means or base of the unit to the forward end of said unit, whereby the completely consumable closure element or wad at said forward end, is instantly burned to open up the unit and permit the fuel to be properly released from said unit for subsequent delivery to the remote point of use in the system being operated.

Another object of the invention is to provide in a power generating unit of the character disclosed, a dual igniting device made up as a unitary structure, and for ignition of the fuel within said power generating unit, whereby said fuel may be ignited or fired by either a percussion cap,

or by electrical igniting means, such as an electric match; the unitary igniting device being so constructed and arranged as to insure ignition of the match heat composition when firing the unit charge by means of percussion.

This and other objects and advantages of this invention will become apparent in the following description, in which the appearance of like reference numerals indicate like parts, and in which:

Figure 1 is a view of a portion of the system assembly disclosed in my aforesaid patent illustrating the cartridge receiving breech block, expansion chamber and cylinder, and the connecting conduit therebetween;

Figure 2 is an enlarged fragmentary sectional view of a form of pressure charge generating unit constructed in accordance with the invention and illustrating particularly a pressure creating unit capable of being ignited either by an electric match or by means of a percussion cap, the same constituting a single unitary device for ignition purposes;

Figure 3 is a detail view in perspective showing the sleeve extension with the V-groove for receiving the bridge wire, as used in the form of the invention illustrated in Figure 2;

Figure 4 is a vertical section of a shell constituting another form of pressure charge generating unit constructed in accordance with this invention and illustrating in particular the tetryl di-chromate lined cellulose tube for use in combination with a match head igniting means;

Figure 5 is a vertical section of a still further form of pressure charge generating unit, illustrating a tubular type of solid pellet with a layer of tetryl di-chromate mixture adhering to the interior bore of said pellet;

Figure 6 is a view in section illustrating a still further modification of the pressure charge generating unit, showing a different form of cellulose igniting tube;

Figure 7 is a fragmentary sectional view of a further modification of the pressure generating unit, showing the cellulose igniting tube in association with a percussion cap instead of a match head igniter; and

Figure 8 is a vertical section of a form of pressure charge generating unit constructed in accordance with the disclosure of Figure 2, and showing the tetryl di-chromate lined cellulose tube surrounding the dual igniting device.

In the particular embodiment of the invention illustrated in Figure 4, A designates a shell comprising a tubular member 5 of cartridge paper or any other suitable material and a ferrule, 6 crimped thereon in any well known way.

This ferrule is provided with a central opening 7 adapted to receive a circuit completing pin 8. Discs 9 and 10 of insulating material are located in the bottom of the shell, and the disc 9 is provided with a safety aperture 11 which aligns with the central opening of the ferrule. A sleeve of insulating material, indicated at 12, is received within these openings and serves to prevent accidental contact of the pin 8 with the metal of the ferrule. A contact strip 14 is disposed between the discs 9 and 10, and a fine bridge wire leads therefrom through a match head composition 16, the bridge wire being continued in the form of a metallic strip 17 back to the ferrule, and said strip being bent into engagement with said ferrule as at 18. It is clear, therefore, that if a shell of this character is placed in a grounded breech block, such as that indicated at 19, in

Figure 1, said ferrule is thus included in a circuit diametrically illustrated at B in Figure 4 and the match head 16 will be ignited when the pin 8 is thrust inwardly to contact with strip 14, the circuit being then completed from the source of E. M. F. indicated at C, from pin 8 through strip 14, match head 16 and ferrule 6 back to the grounded side of the circuit, or in other words, to the breech block.

10 The circuit preferably includes a switch, indicated at D, so that after the shell has been placed in the breech block, the pin 8 may be moved into contact with strip 14 and left in contact with the switch D open. This provides 15 means for distance control of the shell, it being apparent that the match head will be ignited under these conditions, when the switch is closed, either manually or automatically.

The body 5 of the shell contains a burnable, 20 nonexplosive pressure generating fuel E and it is in the characteristics of this fuel that part of the novelty of the present invention resides. One form of fuel which I have found to be highly efficient in accomplishing the objects sought, 25 consist of grains of nitro-glycerine fuel mixed with nitro-cellulose fuel of such size and/or construction and/or relative proportions of sizes as to produce a fuel which, when ignited by the match head, will burn rapidly and generate a very considerable volume of usable propulsive gases without detonation, shock, or jar. I find that by 30 suitably proportioning the sizes of the grains used or by varying the construction of said grains (as for example by piercing them with a greater 35 or less number of small holes) I can control the rate of burning very accurately, and under the present invention I do so control the rate of burning as to discharge from the shell a large quantity of heated gases together with such 40 quantity of the fuel as to carry on combustion and maintain and/or progressively increase the heat volume and pressure of the gases over a desired length of time but without explosion, shock, or jar, and without detonation.

45 Furthermore, I vary the rate of combustion of some of the grains with respect to the rate of combustion of other of the grains, so that the gas from the first burning grains may serve to quickly build up a desired pressure and heat surfaces in contact with which the gases are to come, and the slower burning grains will thereafter maintain the heat of these gases and cause their continued expansion for the performance of the desired work.

55 A further important point of novelty inherent in the present invention is that under certain desired conditions I so arrange the rate of burning of the fuel within the shell 5 that the portion 60 of the fuel first ignited generates sufficient gas before the ignition of the last of the fuel, that any desired part of the fuel is propelled, before being ignited or before being burned, from the shell, and to another point where useful work is to be done and there ignited and/or burned. A shell having the latter characteristics is of 65 particular utility in connection with the structure of Figure 1 where 20 designates a combustion chamber to which the gases discharge from the shell, along with the unconsumed fuel are conducted through a tube, or conduit 21, from the discharge nozzle 22 of the breech block.

70 It will be observed that the tube or conduit 21 constitutes a path of some considerable length and consequently this tube serves as a reservoir within which a considerable volume of gas is gen-

erated prior to the time that a piston 23 within the cylinder 24 and upon which the gases are designed to act, begins to move, so that after the piston begins to move there will be a sufficient volume of gas already created to carry out the desired action of the piston. I have found that the position of the match head 16 in the shell largely determines the amount of fuel which will be consumed within the shell, and the amount which will be propelled from the shell to another point to be consumed at the latter point. That is to say, by locating the match head 16 nearer the front of shell 5 (and this may be accomplished by merely extending the wires leading to said match head) more of the fuel will be consumed within the shell and discharged therefrom as gas and less will be propelled from the shell in unburned form. Such a construction is shown, for instance, at Figure 52 of my Patent No. 2,005,913 of June 25, 1935, where the match head 183 is directly beneath and in close proximity to the combustible wad over the end of the shell. From experience and tests, however, this construction has been found to be impracticable for commercial use, and this due to the melting of the solder on the match head or to the burning through of the lead wires which for the entire length of the shell are subjected to the intense heat of the charge 185 contained within the shell shown in said Figure 52 of my patent just mentioned. Due to these last mentioned conditions, pieces of metal in the match head frame are loosened and become detached and are invariably carried into the system and the starter operating mechanism, thereby causing considerable trouble.

The ignition means hereinbefore mentioned comprises a match head composed of cuprous-acetylidy covered with a coating of a mixture of approximately 75% tetryl and 25% potassium di-chromate or bi-chromate or chromate mixed in fine powdered form with a suitable binding material which will adhesively bind the composition in place as a formed and shaped match head.

The frame of the match head, including its bridge wire, is first dipped in a solution of cuprous-acetylidy or other non-corrosive substance ignitable at approximately 450° F. which insures a sufficient flame to ignite a coating thereto composed of any non-deleterious composition which will burn with a hot flash of prolonged duration. This coating is obtained by again dipping the frame of the match head into a mixture of approximately 75% tetryl and approximately 25% of potassium di-chromate or bi-chromate or chromate mixed in powdered form with a suitable binder, such as, for example, collodion liquid nitro-cellulose or any other binding material which will cohesively bind the whole together as an operative match head. It is important that the compositions forming this match head are such that they will neither of their own account nor by admixture with the formulated gases of the other fuels in the shell form a deleterious gas which will deteriorate the metal or other component parts of the device with which the shell is used.

The type of fuel in the shell is such that if in a cartridge of given diameter, the body of the fuel is sufficiently deep or long, the individual grains of fuel may bind themselves on the side of the shell casing and in such eventuality a considerable amount of undesirable pressure will be generated at the back of the fuel (base of the cartridge), before the fuel will start moving out of the shell. Such a condition obviously exerts

a tendency to break up the fuel and creates an undesirable pressure condition sufficient to blow the fuel out of the shell in a wad formation instead of a steady stream desirable for smooth operation in the system. I have found in actual practice that a longer sized or deeper shell is necessary under cold or extreme cold weather conditions and I have further provided, for use in combination with this match head a completely disintegrating and consumable tube 19' composed of nitro-cellulose film or other similar or suitable substance, internally coated with a mixture of tetryl di-chromate or tetryl bi-chromate in the respective proportions of approximately 75% tetryl and 25% di-chromate. This tetryl di-chromate lined cellulose tube is operatively placed over the match head at the base of the shell and extends to the consumable wad 20 which forms the closure. I am thus enabled to elongate the steady hot flame from the rear of the shell to the front of the shell and thereby insure initial ignition of the shell pellets disposed at the front or the forward end of the shell. Also, by the use of this tube I am enabled, immediately upon initiating ignition of the unit charge, to conduct the hot flash flame through said tube from the point of ignition to the forward end of the shell, where said flame instantly burns the completely consumable closure element or wad and permits the immediate and proper release of the ignited fuel charge from the shell for subsequent delivery to the place of burning for creating gases to perform a useful work operation. I prefer in the longer type of shell to place the majority of the nitro-glycerine bearing fuel in the front end of the shell so as to further insure ignition of the fuel in the front portion of the shell and thereby support the ignition of the nitro-cellulose fuel from the front as well as from the rear as in the shorter type of shell. This tube may be made of spiral wound nitro-cellulose film, or it may be a nitro-cellulose tube formed by extrusion; furthermore, it may be formed of double base material of the same composition as that of double base nitro-glycerine bearing nitro-cellulose powder or fuel; and/or this tube may be lined with a mixture of tetryl di-chromate or tetryl chromate mixture and mixed with a suitable binder such as a liquid nitro-cellulose or other combustible consumable binder. Furthermore, said tube may be lined or coated on the inside, or it may be lined or coated on the inside, and/or coated on the outside. Still further, said tube may be lined with a suitable mixture of zirconium and a suitable oxidizer such as barium nitrate or chromate or di-chromate, and the tube treated with this mixture the same as described for tetryl and di-chromate. By the use of zirconium and a suitable oxidizer, together with a suitable binder, it is possible to secure a more rapid conductance of the flame from the primary igniter area to the forward end of the shell.

Further than the above, it is well to note from the operation of this type of power generating unit, that when the match head 16 is ignited a clear path through the center of the tube 19' is provided extending to the forward end of the shell, and not only the flame of the match head 16, but also the flame from the tube and tube liner of tetryl dichromate, proceed at once to the forward end of the shell to immediately burn a hole through the consumable wad 20. At the same time, the burning of the tube 19' creates a train of fire for practically the entire length of the shell

and ignites the fuel in contact therewith or in close proximity to said tube 19.

Also in the use of this tube it is desirable to place the double base or nitro-glycerine bearing, easily ignitable, booster or kindling fuel, in the forward end of the shell (instead of at the rear around the match head 16), so that by igniting this fuel in the forward end of said shell, the remainder of the fuel charge at the rear will be withdrawn from the shell by suction into the system as the burning of the fuel progresses. From actual experiments and experience, this action has been found to take place.

The tube may also be placed in a shell of the character described, with the lower end of the tube surrounding a percussion type of initiator (instead of a match head), such for instance, as shown at 21 in Figure 7 of the drawings, the tube in this figure being designated at 19a.

In the solid pellet type of fuel, such as shown in Figure 5, the lining 22 of the solid pellet 23 may be of tetryl di-chromate or zirconium and an oxidizer as heretofore described in connection with the tube 19'. This lining may also be in the form of a coating, or it may be a thin film or layer of double base or nitro-glycerine bearing nitro-cellulose fuel, and furthermore, may be made as an integral part of the solid pellet 23 by the extrusion method. The solid pellet 23 may be made of straight nitro-cellulose fuel, and on the outer end of said pellet, as shown in Figure 5, there may be provided a cap or wafer 24 made of nitro-glycerine bearing double base fuel, which is easily ignitable, and which would serve to insure the ignition of the front or forward end of the solid pellet 23, after the action of the tube 22 has taken place as heretofore described for igniting purposes. This wafer 24 has a hole therethrough of the same size as the bore of the solid pellet 23 and as a matter of fact said hole forms an extension of the bore. It is also well to note in this connection that the lining or coating just referred to extends over the interior surface of said pellet and up to and through the hole formed in the wafer. The match head used in connection with this type of power generating unit is shown at the bottom of the solid pellet, and indicated at 25 in Figure 5.

The gist of the invention as pertaining specifically to the match head is that I provide thereby a match head in which no chlorates or other deleterious matter is present and which burns with a prolonged and elongated hot flame in an ordinary weather type of shell. In addition thereto, I have provided completely consumable tube means for securing the necessary prolonged hot flame to properly insure ignition without a prior building up of pressure in the longer and deeper cold or extreme cold weather type of shell. The means here provided enables me to ignite and burn fuels which are, as is well known, normally susceptible to the phenomena of explosive chemical reaction without approaching an explosive chemical reaction or disturbing the explosive chemical equilibrium of the fuel.

It is well to note that I have found by experience that the ordinary type of match head is undesirable and useless for the purpose of this invention in that the ordinary match head usually contains chlorates, ignites with a snap which is highly akin to detonation, does not produce a prolonged and elongated hot flame as is necessarily secured by the match head described herein, and in actual practice the ordinary and known match head results in breakage of the associated

mechanism with which I prefer to use my shell.

In the form of the invention illustrated in Figure 2 of the drawings, I have provided a new type of initiator or igniting means for the power generating charge 25a within the shell 26, this initiator capable of being fired either electrically or by percussion, and the same being made as a single unitary structure. In this Figure 2, a conventional percussion type of initiator is shown at 27, with the outer shell of the priming cap indicated at 28, and the center of the point where the striker or firing pin initiates the priming cap by concussion being indicated at 29. Also at 30 is shown a pin which serves not only as the firing pin for the percussion type of firing, but also as the hand operated electrode for the electric type of firing. A brass or other metal sleeve 31 surrounds the percussion cap 27 and is insulated therefrom by means of an insulator 32 of fiber, paper or some other suitable insulating material, the parts being rigidly held together as a unitary structure, which device may be pressed through a central opening in the metal ferrule 33 of one of my conventional cartridge type power generating units.

The sleeve 31 and the ferrule 33 of the cartridge shell are in close electrical contact, and extending from the sleeve is an extension 34 having a V-groove 35 for receiving one end of a bridge wire 36, the other side of said bridge wire being received within a V-groove 37 formed within an extension 38 of the priming cap 27. After the bridge wire is inserted within the V-grooves of the extensions 34 and 38, the two legs of each V-grooved extension are pinched together to hold the bridge wire 36 firmly in place, and thus make electrical connection between the sleeve 31 and the priming cap 27. This bridge wire may also be soldered to the extensions 34 and 38 as indicated at 39 in Figure 3, after which said bridge wire and the extensions 34 and 38 are dipped in a composition of cuprous acetylide, then dried, and afterwards dipped in a composition of tetryl di-chromate or other suitable hot flash composition, thus forming a match head of the character herein referred to, the cuprous acetylide coating being indicated at 40 and tetryl di-chromate coating indicated at 41. In this connection it is well to note that the cuprous acetylide ignites at a low temperature and in its burning operation produces a sufficient heat and flame to ignite the outer match head coating 41 of tetryl di-chromate or other suitable hot flash composition which burns with a hot flame instead of an explosion.

The combustible substance in the priming cap chamber is composed of any one of several well known percussion types of materials, which when fired expel a long hot flame through the orifice 42 at the outer end of said priming cap.

It is clear, therefore, that if a shell of this character is placed in a grounded breech block such as indicated at 19, in Figure 1, the ferrule 33 is thus included in an electric circuit, and the match head will be ignited when the firing pin 30 is placed in contact with the priming cap, a suitable source of electrical current being provided for this purpose.

In this embodiment of the invention it will thus be seen that I have provided in a unitary structure a device having dual ignition means, whereby the power generating unit may either be fired electrically (as for instance, by an electric match) or else by means of the percussion type of ignition.

In the event it is desired to use the electrical

ignition, said ignition is accomplished by passing an electrical current from the firing pin 30, through the percussion cap frame 27, the extension 38, bridge wire 36, the extension 34, sleeve 31, and thence to the metal ferrule 33 of the shell back to the grounded side of the circuit, or in other words, to the breech block.

If for any reason the electrical ignition does not function, firing pin 30 may be suitably drawn back and snapped in a well known way, and by percussion fire the percussion powders in the primer cap 27, projecting a flame through the orifice 42 which will ignite the match head and also the kindling and other fuel located within the shell and within range of said flame.

An asbestos wad 43 is placed in the bottom of the shell to act as a cushion or seal around the metal sleeve 31, and to prevent the shell from leaking around the priming device.

It is also an embodiment of this invention to place a tube of the character described and of suitable length within a shell, and with the lower end of said tube surrounding a match head type of initiator, and with the upper end of the tube cemented or otherwise secured to the side of the cartridge shell. Such a tube is shown for instance at 19^b in Figure 6 of the drawings, and the point of cementing the tube to the side of the shell is indicated at 44, in said figure.

It is also well to note that in Figure 8 of the drawings, a tube of the character described herein is illustrated at 19^c, and that this tube surrounds a dual igniting means of the type illustrated in Figure 2 of the drawings, the dual igniting means being indicated generally at 45 and the tube extending therefrom and through the fuel within the shell in a direction longitudinally of said shell, and for the purposes heretofore set forth.

In the drawings the nitro-glycerine bearing fuel pellets (easily ignitable and hard to extinguish) are shown as shaded pellets, thus indicating their preferable location with respect to the nitro-cellulose fuel pellets and the other elements of the power generating units herein described, said nitro-cellulose fuel pellets being unshaded.

What I claim and desire to secure by Letters Patent is:

1. In a power generating unit of the character described, a shell, a body of difficultly ignitable deflagrating main fuel of a material of such nature that its rate of burning increases with increase of pressure, a deflagrating kindling fuel associated with said main fuel, a primary igniting means at the base of said shell, and a nitro-cellulose tube lined with tetryl di-chromate associated with said igniting means and extending through the body of main fuel for insuring proper ignition of the fuel charge at the forward end of said shell.

2. In a power generating unit of the character described, a shell, containing a charge of deflagrating burnable fuel in such quantity to deliver, when ignited and burned, a sufficiently large volume of gas to perform an appreciable amount of useful work and wherein said fuel is composed of a multiplicity of pellets some of which are faster burning than others and adapted to aid in maintaining ignition and support combustion of the slower burning pellets, a primary igniting means at the base of said shell, and a nitro-cellulose tube lined with tetryl di-chromate associated with said igniting means and extending through the charge of fuel for insuring proper ignition of the faster burning pellets within said shell.

3. In a power generating unit of the character described, a shell containing a charge of deflagrating burnable fuel in such quantity to deliver, when ignited and burned, a sufficiently large volume of gas to perform an appreciable amount of useful work and wherein said fuel is composed of a multiplicity of pellets some of which are faster burning than others and adapted to aid in maintaining ignition and support combustion of the slower burning pellets, a hot flash means at the base of said shell, and a nitro-cellulose tube lined with tetryl di-chromate associated with said hot flash means and extending longitudinally through the charge of fuel for insuring proper ignition of the faster burning pellets within said shell.

4. In a power generating unit of the character described, a shell containing a charge of deflagrating burnable fuel in such quantity to deliver, when ignited and burned, a sufficiently large volume of gases to perform an appreciable amount of useful work and wherein said fuel is composed of a multiplicity of pellets some of which are faster burning than others and adapted to aid in maintaining ignition and support combustion of the slower burning pellets, a primary igniting means at the base of said shell, and a secondary igniting means associated with said primary igniting means and extending longitudinally through the charge of fuel for insuring, when burning, the ignition of the fuel within said shell.

5. In a power generating unit of the character described, a shell containing a charge of deflagrating burnable fuel in such quantity to deliver, when ignited and burned, a sufficiently large volume of gas to perform an appreciable amount of useful work and wherein said fuel is composed of a multiplicity of pellets some of which are faster burning than others and adapted to aid in maintaining ignition and support combustion of the slower burning pellets, said faster burning pellets being located at the forward end of said shell, a primary igniting means, and a kindling means ignited by the igniting means and extending through said charge of fuel to insure, when burning, the ignition of the faster burning pellets within said shell.

6. In a power generating unit of the character described, a projectile free shell containing a body of deflagrating main fuel, a kindling fuel associated with said main fuel, a primary igniting means at the base of said shell, and a burnable fuel tube of material capable of being completely consumed without ash or other objectionable residue ignited by said primary igniting means and extending through the body of main fuel toward the forward end of said shell to insure proper ignition of the kindling fuel, said tube being unobstructed to permit the flash from the primary igniting means to be properly projected therethrough.

7. In a power generating unit of the character described, a projectile free shell containing a body of deflagrating main fuel in such quantity as to deliver, when ignited and burned, a volume of gas to perform an appreciable amount of useful work, a kindling fuel associated with said main fuel at the forward end of the shell, a primary igniting means at the base of said shell, and a burnable fuel tube of material capable of being completely consumed without ash or other objectionable residue ignited by said igniting means and extending through the body of main fuel to a point adjacent the kindling fuel to in-

sure ignition thereof, said tube being unobstructed to permit the flash from the primary igniting means to be properly projected therethrough.

8. In a power generating unit of the character described, a projectile free shell containing a charge of deflagrating burnable main fuel in such quantity to deliver, when ignited and burned, a sufficiently large volume of gas to perform an appreciable amount of useful work, an electric match igniting means at the base of the shell including a match head, an unobstructed burnable fuel tube of material capable of being completely consumed without ash or other objectionable residue surrounding said match head and extending longitudinally of the shell and through the fuel charge within said shell for conveying a hot flash flame from said match head and the tube, when ignited, to the forward end of said shell, and a kindling fuel associated with said main fuel and located adjacent the forward end of said tube.

9. In a power generating unit of the character described, a shell containing a charge of deflagrating burnable fuel in such quantity to deliver, when ignited and burned, a sufficiently large volume of gas to perform an appreciable amount of useful work, a primary igniting means at the base of said shell, and a nitro-cellulose tube lined with tetryl di-chromate associated with said igniting means for use as a conveying means for a hot flash flame from said primary igniting means to the forward end of the shell and also serving to insure proper ignition of the fuel charge within said shell.

10. In a power generating unit of the character described, a projectile free shell containing a charge of deflagrating burnable fuel in such quantity to deliver, when ignited and burned, a sufficiently large volume of gas to perform an appreciable amount of useful work, an igniting means at the base of the shell, and a tube of material capable of being completely consumed without ash or other objectionable residue when burned and surrounding and extending from said igniting means through the body of fuel with the outer end of said tube closely adjacent and anchored to the side of the shell at a point short of the forward end of said shell.

11. A power generating unit of the character described, a shell, a solid body of difficultly ignitable main fuel within said shell and having a bore therethrough arranged longitudinally of said shell, a film or coating of tetryl di-chromate upon the interior bore of said fuel, an igniting means at the base of said shell extending into the bore at the lower end of said body of fuel, and a wafer of nitro-glycerine bearing double base fuel at the forward end of said shell and associated with said solid body of fuel, the tetryl di-chromate lining or coating also extending through the wafer.

12. A power generating unit of the character described, a shell, a solid body of difficultly ignitable main fuel within said shell and having a bore therethrough arranged longitudinally of said shell, a film or coating of tetryl di-chromate upon the interior bore of said fuel, and an igniting means at the base of said shell extending into the bore at the lower end of said body of fuel.

13. A power generating unit of the character described, a shell containing a body of deflagrating fuel in such quantity as to deliver, when ignited and burned, a volume of gas to perform an appreciable amount of useful work, a percussion cap associated with the base of said shell having

an orifice through which is projected a hot flash flame for igniting said fuel when the percussion cap is fired, and a match head located within the shell for producing a second and independent hot flash flame within the shell when ignited for igniting the fuel, said match head being so associated with the percussion cap as to be ignited by the hot flash flame projected through the orifice of said percussion cap.

14. A power generating unit of the character described, a shell containing a body of deflagrating fuel in such quantity as to deliver, when ignited and burned, a volume of gas to perform an appreciable amount of useful work, a percussion cap associated with the base of said shell having an orifice formed therein through which a hot flash flame may be projected within the shell to ignite said fuel, and an electric match mounted on said percussion cap and insulated therefrom so as to be fired electrically, the head of said electric match being so positioned with respect to the percussion cap orifice as to be ignited by the hot flash flame projected through said orifice and simultaneously with the ignition of said fuel for projecting a second hot flash flame within the shell for ignition purposes.

15. In a power generating unit of the character described, a shell containing a charge of deflagrating burnable fuel in such quantity to deliver, when ignited and burned, a sufficiently large volume of gas to perform an appreciable amount of useful work, a primary igniting means at the base of said shell, and means having a tetryl di-chromate coating associated with said igniting means for use as a conveyor for a hot flash flame from said primary igniting means to the forward end of the shell and also serving to insure proper ignition of the fuel charge within said shell.

16. In a power generating unit of the character described, a projectile free shell containing a body of deflagrating fuel in such quantity as to deliver, when ignited and burned, a volume of gas to perform an appreciable amount of useful work, an inflammable closure for said shell, an igniting means for said fuel, and an unobstructed burnable and completely consumable tube within the shell and extending through the fuel for conveying the flame from said igniting means toward the closure end of said shell for also igniting the closure, said tube when burned leaving no ash or other objectionable residue in the gas being generated.

17. In a power generating unit of the character described, a projectile free shell containing a body of deflagrating fuel in such quantity as to deliver, when ignited and burned, a volume of gas to perform an appreciable amount of useful work, an inflammable closure for said shell, an igniting means at the base of the shell for igniting the fuel, and burnable and completely consumable means unhampered by the fuel for causing the flame of said igniting means to simultaneously ignite the closure, said completely consumable means when burned leaving no ash or other objectionable residue in the gase being generated.

18. In a power generating unit of the character described, a projectile free shell containing a body of deflagrating fuel in such quantity as to deliver, when ignited and burned, a volume of gas to perform an appreciable amount of useful work, an inflammable closure for said shell, an igniting means for said fuel, and an unobstructed burnable and completely consumable tube within said shell and extending through the fuel for conveying the flame from said igniting means toward

the closure end of said shell for also igniting the closure, said tube coated with a substance to promote and sustain said flame along the tube, and said tube and its coating being of such character when burned as to leave no ash or other objectionable residue in the gas being generated.

19. In a power generating unit of the character described, a projectile free shell containing a body of deflagrating fuel in such quantity as to deliver, when ignited and burned, a volume of gas to perform an appreciable amount of useful work, an inflammable closure for said fuel, an igniting means for said fuel, and an unobstructed burnable and completely consumable tube extending longitudinally through the fuel for conveying the flame from said igniting means toward the forward end of said shell for simultaneously igniting said closure, said tube being of such character when burned as to leave no ash or other objectionable residue in the gas being generated.

20. In a power generating unit of the character described, a projectile free shell containing a body of deflagrating fuel in such quantity as to deliver, when ignited and burned, a volume of gas to per-

form an appreciable amount of useful work, an inflammable closure for said fuel, an igniting means for said fuel, and an unobstructed burnable and completely consumable tube extending longitudinally through the fuel for conveying the flame from said igniting means toward the forward end of said shell for simultaneously igniting said closure, said tube coated with a substance to promote and sustain said flame along the tube.

21. In a power generating unit of the character described, a projectile free shell containing a body of deflagrating fuel in such quantity as to deliver, when ignited and burned, a volume of gas to perform an appreciable amount of useful work, an igniting means for said fuel, and burnable and completely consumable means extending longitudinally within the shell for conveying the flame from said igniting means toward the outer end of said shell, said burnable means coated with a substance to promote and sustain the flame to properly ignite the fuel within the shell.

ROSCOE A. COFFMAN.
